UNITED STATES PATENT OFFICE.

STANLEY M. CRITES, OF ST. MARTINVILLE, LOUISIANA.

POLE-ANCHOR.

1,105,884.

Specification of Letters Patent.

Patented Aug. 4, 1914.

Application filed January 8, 1913. Serial No. 740,821.

To all whom it may concern:

Be it known that I, STANLEY M. CRITES, a citizen of the United States, residing at St. Martinville, in the parish of St. Martin and State of Louisiana, have invented certain new and useful Improvements in Pole-Anchors, of which the following is a specification.

This invention relates to earth anchors of the type which are used to hold the lower ends of pole braces such as are frequently used in connection with telegraph and telephone poles.

The principal object of the invention is to provide an improved device of this character wherein arrangement is made so that the cross member or fluke of the anchor may be placed in position without disturbing the earth lying in the direction of the stress exerted by the brace wire or cable.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and Figure 1 is a side elevation of the device in use, the earth being shown in section. Fig. 2 is a transverse detail showing the parts in position on an enlarged scale. Fig. 3 is a view of the parts disassembled.

In carrying out the object of this invention there is provided a rod 10 having an eye 11 formed at one end for the attachment of the brace wire or cable. At the other end of this rod there is provided an opening 12 for the reception of a pin 13 and this pin has the head 14 slightly upset to prevent its dropping through the opening 12. In connection with the rod 10 there is used a cuff 15 of elliptical form and provided at one end of its shorter axis with an opening 16 for the reception of the lower end of the rod. There is also provided a pointed stake 17 which is of such size that it will pass through the cuff when the rod is in position

and will project a considerable distance on either side of said cuff. This stake constitutes the anchor fluke.

In using the device the earth is removed at 18 so that a hole is formed extending at right angles to the line draft which will be exerted by the brace wire 19. The cuff is then placed at the bottom of this hole and the rod 10 driven through the earth until its lower end projects into the opening in the earth, whereupon its end is fitted into the opening 16 of the cuff. The pin 13 is then inserted through the opening 12 and the pointed stake 17 driven into position so that it projects into the undisturbed portion of the earth. The opening in the ground may then be filled and tamped solidly when it will be plain that great stress may be exerted upon the wire 19 without disturbing the anchor because of the large body of undisturbed earth between the anchor fluke and the eye 11. It will also be obvious that by reason of the elliptical shape of the cuff a greater cross sectional area is obtained to resist withdrawal and furthermore a flattened stake may be used for the same purpose. It will also be noted that the rod 10 forms the stock of the anchor.

There has thus been provided a simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed.

Having thus described the invention, what is claimed as new, is:—

1. In an earth anchor, the combination, with a stock consisting of a rigid rod; of a cuff, means for connecting said rod and cuff after the rod has been driven into earth, and a fluke consisting of a pointed stake extending at right angles to the stock and movable through said cuff.

2. In an earth anchor, the combination with a stock consisting of a rigid rod adapted to be driven through earth to penetrate an opening formed substantially at right angles to the line of drive, of a cuff, means for connecting the penetrating end of said rod and the cuff when the rod is in position in the earth, and a fluke consisting of a pointed

stake extending at right angles to the stock and movable through the cuff.

In testimony whereof I affix my signature in presence of two witnesses.

STANLEY M. CRITES.
